ATTORNEY

UNITED STATES PATENT OFFICE.

WILLIAM OZE BROYLES, OF BIRMINGHAM, ALABAMA.

SHOCK-ABSORBING BED.

Application filed April 23, 1920. Serial No. 376,157.

To all whom it may concern:

Be it known that I, WILLIAM O. BROYLES, a citizen of the United States of America, residing at Birmingham, in the county of 5 Jefferson and State of Alabama, have invented certain new and useful Improvements in a Shock-Absorbing Bed, of which the following is a specification.

My invention relates to an improved type 10 of bed having a supporting means capable of absorbing or minimizing shocks and vibrations so that the occupant of the bed will not be disturbed or annoyed thereby.

I have found in many instances, especially 15 in the case of patients at hospitals and of persons troubled with nervous diseases and insomnia, that their rest is greatly disturbed by the jars and vibrations which are transmitted to them through the bed, and particularly through metal beds.

I have conceived that if a bed can be produced, without greatly increasing its cost or making it unattractive in appearance as compared with the standard bed, which will 25 protect its occupant from jolts and jars, it will fill a widespread present need, and to this end I have designed a bed which, in its preferred form, comprises two frames, one forming a support having preferably the 30 general appearance of a bed frame, and the other forming the bed proper which is so mounted on the supporting frame as to accomplish the ends in view as aforesaid. The support may be formed by any suitable 35 element whether attached to or forming part of the building or compartment in which the bed is located.

My invention is capable of embodiment in various designs and materials and it is therefore 40 to be understood that in this specification I have sought merely to illustrate formally what I have so far found to be the preferred embodiment of my invention.

According to the drawings:—

45 Fig. 1 illustrates a bed in accordance with my invention viewed in perspective.

Fig. 2 is a partial side elevation of one end of the bed illustrating a typical shock absorbing broken joint connection between 50 the bed and its support.

Fig. 3 is a sectional view shown in partial end elevation of one corner of the bed.

Similar reference numerals refer to similar parts throughout the drawings.

55 The bed as illustrated is composed of two

main elements, one being the supporting element which rests on the floor and the other the supported element which carries the springs and mattress and forms the bed proper.

The supporting element, as illustrated, comprises similar head and foot frames 1 which are formed of an inverted U-shape from standard metal tubing provided at their lower ends with casters 2 and with joint members 3 for engagement with standard side rails 4. It is to be noted that these side rails 4 are connected to the frames 1 near the floor, and this is preferable by reason of the fact that the bed proper is suspended from the upper portions of the head and foot members 1 and by this arrangement the latter are more capable of yielding towards each other and of exerting a greater bending stress of the side rails 4 to thereby cause the supporting frame itself to be substantially yielding or spring-like and thus itself, if necessary, forming the sole absorbing shock support for the bed proper.

The supported element of the bed, which may be more accurately termed the bed proper, is of standard bed construction with the exception that the posts of its head and foot frames 5 are extended only a short distance below the point of connection therewith of the side rails 6. The side rails 6 of the bed proper are appreciably shorter than the side rails 4, thus permitting the bed proper to be suspended free for limited movement between the head and foot frames 1, hanger rods 7 being used as the suspension means and having their lower hook ends adapted to engage in the open lower ends of the posts of the head and foot frames 5 while their upper ends are suitably connected to the sides of the head and foot frames 1 near their top, this connection preferably being made to hooks 8 with short coil springs 9 interposed as a connecting link.

By reason of the fact that the load strain from the bed proper is sustained directly by the posts or sides of the head and foot frames 1, the latter frames do not need to be cross connected and can be formed as shown by a single arch, but the head and foot frames 5 of the bed proper are cross connected as usual and preferably are in every respect of standard design with the present head and foot frames of metal beds. The bed proper is so suspended as to have

the necessary free play laterally and endwise to prevent contact with the supporting frame proper and is adapted to receive the usual bed springs so that when the bed is made up it is not materially dissimilar in appearance from the present standard beds.

I claim for this improved type of bed that the spring or yielding support of the bed proper will absorb all jolts and jars and 10 permit the patient to rest with a delightful sense of ease quite impossible to attain with the present standard type of bed.

The distinctive feature of my invention is that the bed proper shall be so supported by 15 the supporting element, whatever it may be, as to avoid the transmission of shocks and this may be done as shown or by any non-rigid or broken joint connection which will prevent the appreciable conduction of vibration or shock from the floor or support to 20 the bed proper.

This invention is not intended to be restricted in scope to the specific embodiments shown, but contemplates such modifications 25 as come within the spirit and scope of the claim.

Having thus described my invention, what I claim as new and desire to secure by Letters Patent, is:—

In a bed of the character described, a bed 30 proper comprising rails, head and foot members having vertical tubular side posts projecting just below the side rails and left open at their lower ends, a supporting element in the form of a bed frame having head and 35 foot members spaced to permit the bed proper to swing freely lengthwise between them, and having side rails connecting its head and foot members below the level of said side posts, and hangers connected at 40 each side to the upper portion of the head and foot members of the supporting element, each hanger comprising a coil spring, and a rod having its lower end bent to project upwardly into the open bottom end of 45 a side post to thereby suspend the bed proper free for predetermined lateral endwise and vertical play.

In testimony whereof I affix my signature.

WILLIAM OZE BROYLES.
